UNITED STATES PATENT OFFICE.

JOHN WILLIAM LITTLER, OF BROADHEATH, ENGLAND, ASSIGNOR TO LINOTYPE AND MACHINERY LIMITED, OF LONDON, ENGLAND.

FLAT-BED PRINTING PRESS.

1,409,743.

Specification of Letters Patent. Patented Mar. 14, 1922.

Application filed January 8, 1921. Serial No. 435,789.

To all whom it may concern:

Be it known that I, JOHN WILLIAM LITTLER, a subject of the King of the United Kingdom of Great Britain and Ireland, and residing at Linotype and Machinery Works, Broadheath, in the county of Chester, England, have invented new and useful Improvements in Flat-Bed Printing Presses, of which the following is a specification.

10 This invention relates to flat bed printing presses, and has for its object to provide an improved construction of the known type in which the bearers in such presses fulfil the dual capacity of bearers and side bars so as 15 to dispense entirely with the separate side bars which are generally employed and to a corresponding extent serve for increasing the space available for receiving the form.

The invention will now be described by 20 reference to the accompanying drawings, in which:—

Figure 1 is a plan, partly broken away, of a type bed fitted with the improved bearers and cross-bars;

25 Figure 2 is a front elevation of the arrangement shown in Figure 1, and

Figure 3 is a section on the line 3—3 of Figure 1, drawn to a larger scale than that figure.

30 According to the present invention, the cylinder bearers 2, 3 secured to the type bed 1 are provided with recesses 4, 5 respectively to enable them to serve as side bars for the locking up of the form. The recesses 4, 5 35 are formed, as shown best in Figure 3, with inwardly facing mouths, so that the tops or tracks of the bearers 2, 3, present the usual uninterrupted surfaces and also prevent the cross-bars 6, 7, from working out 40 upwardly. The ends of the cross-bars 6, 7, are bevelled as shown to permit of their readily entering the recesses 4, 5, when the bars are moved longitudinally, and the recesses in one of the bearers, say the recesses 45

5 in the so-called gear side bearer 3, are deeper than are the corresponding recesses 4 in the opposite or feeder side bearer 2, to allow of the just-named longitudinal movement for the disengagement of the respective

50 cross-bar first from one and then from the other of the two recesses with which it is engaged and reversely for the engagement of the said bar therewith. In the ex-

ample illustrated, the rear cross-bar 7, being wider than the recesses 4, 5, engages the latter by projections at its ends, the projection on the end adjacent to the deeper recess 5 being longer than that at the opposite end, to permit of the endwise engaging and disengaging movement of the said bar. 60

For the purpose of securing the cross-bars 6, 7 in position for locking up a form, each has pivoted to it, as by a shouldered screw 9, a catch or stop 8 in such a position that it may be engaged with the respective 65 bearer as shown in the drawing in full lines to prevent endwise movement of the respective cross-bar, or turned on its pivot to the position in which it is shown in dot-and-dash lines in Figure 2 to permit the removal of 70 the bar. The inner ends of the catches 8 may be conveniently provided with tails bevelled as shown in Figures 2 and 3 to limit their pivotal movement when the cross-bars 6, 7 are in position on the type 75 bed 1.

The cross-bar 6 at the front edge of the type bed 1 is preferably provided on one of its edges with inclined surfaces 11 which, when the bar is used in the position illustrated in Figure 1, that is to say with the said inclined surfaces presented towards the cross-bar 7, serve as wedge surfaces for locking up the form when the locking-up furniture used consists of wooden 80 wedges, or quoins. Where, however, expandable metal quoins are employed for locking up the form, such wedge surfaces are not required and the bar 6 may then be reversed end for end so as to present 85 its straight edge inwards. In order that the cross-bar 6 may be locked when in the last-named reversed position a tapped hole 10 may be provided in a convenient position on the appropriate inclined surface 11 so 90 that the catch 8 may be readily attached to that edge of the bar when required.

It is to be understood that the precise construction herein described and illustrated in the accompanying drawings is given merely 100 as an example, and may be varied within the scope of the invention.

Having described my invention, I declare that what I claim and desire to secure by Letters Patent is:—

1. In a flat bed printing press, the com-

- bination with the bed of cylinder bearers 85 provided with recesses adapted to accommodate the ends of cross-bars for locking up the form with a capacity for endwise movement of the crossbars in such recesses.
- 5 2. In a flat bed printing press, the combination with the bed and a cylinder bearer on each side thereof, of oppositely-located recesses in the respective bearers, cross-bars 70 adapted to engage said recesses with a capacity for endwise movement in the latter, and means adapted to lock said cross-bars against endwise movement when so engaged.
- 10 3. In a flat bed printing press, the combination with the bed and a cylinder bearer on each side thereof, of a series of recesses in one of the bearers, a corresponding series of deeper recesses in the other bearer, and cross-bars adapted to be engaged with and 75 disengaged from oppositely-located pairs of such recesses by endwise movement relatively thereto.
- 15 4. In a flat bed printing press, the combination with the bed and a cylinder bearer on each side thereof, of a series of recesses in one of the bearers, a corresponding series of deeper recesses in the other bearer, cross-bars adapted to be engaged with and 80 disengaged from oppositely-located pairs of such recesses by endwise movement relatively thereto and means adapted to lock said cross-bars against endwise movement when so engaged.
- 20 5. In a flat bed printing press, the combination with the bed and a cylinder bearer on each side thereof forming an uninterrupted track for the cylinder, of oppositely-located inwardly-opening recesses in the respective 85 bearers, and cross-bars adapted to engage said recesses with a capacity for endwise movement in the latter.
- 25 6. In a flat bed printing press, the combination with the bed and a cylinder bearer on each side thereof forming an uninterrupted track for the cylinder, of a series of inwardly-opening recesses in one of the bearers, a corresponding series of deeper inwardly-opening recesses in the other bearer, cross-bars adapted to be engaged with and 90 disengaged from oppositely-located pairs of such recesses by endwise movement relatively thereto, and a pivoted catch on each cross-bar adapted to engage with a bearer to prevent endwise movement of the respective bar 95 when so engaged.
- 30 7. In a flat bed printing press, the combination with the bed and a cylinder bearer on each side thereof forming an uninterrupted track for the cylinder, of a series of inwardly-opening recesses in one of the bearers, a corresponding series of deeper inwardly-opening recesses in the other bearer, cross-bars adapted to be engaged with and 100 disengaged from oppositely-located pairs of such recesses by endwise movement relatively thereto, and a pivoted catch on each cross-bar adapted to engage with a bearer to prevent endwise movement of the respective bar 105 when so engaged.
- 35 8. In a flat bed printing press, the combination with the bed and a cylinder bearer on each side thereof, forming an uninterrupted track for the cylinder, of oppositely-located inwardly-opening recesses in one of the bearers, a corresponding series of deeper inwardly-opening recesses in the other bearer, cross-bars adapted to lock said cross-bars against endwise movement when so engaged.
- 40 9. In a flat bed printing press, the combination with the bed and a cylinder bearer on each side thereof, of oppositely-located recesses in the respective bearers, cross-bars 110 adapted to engage said recesses, and a pivoted catch on each cross-bar adapted to engage with a bearer to prevent endwise movement of the respective bar when so engaged.
- 45 10. In a flat bed printing press, the combination with the bed and a cylinder bearer on each side thereof, of a series of recesses in one of the bearers, a corresponding series of deeper inwardly-opening recesses in the other bearer, cross-bars adapted to be engaged with and 115 disengaged from oppositely-located pairs of such recesses by endwise movement relatively thereto, and a pivoted catch on each cross-bar adapted to engage with a bearer to prevent endwise movement of the respective bar 120 when so engaged.
- 50 11. In a flat bed printing press, the combination with the bed and a cylinder bearer on each side thereof, forming an uninterrupted track for the cylinder, of a series of inwardly-opening recesses in one of the bearers, a corresponding series of deeper inwardly-opening recesses in the other bearer, cross-bars adapted to be engaged with and 125 disengaged from oppositely-located pairs of such recesses by endwise movement relatively thereto, and a pivoted catch on each cross-bar adapted to engage with a bearer to prevent endwise movement of the respective bar when so engaged.
- 55 12. In a flat bed printing press, the combination with the bed and a cylinder bearer on each side thereof forming an uninterrupted track for the cylinder, of oppositely-located inwardly-opening recesses in the respective bearers, cross-bars adapted to engage said recesses, and a pivoted catch on each cross-bar adatped to engage with a bearer to prevent endwise movement of the respective bar when so engaged.
- 60 13. In a flat bed printing press, the combination with a bed and a cylinder bearer on each side thereof, of oppositely-located recesses in the respective bearers, a cross-bar adapted to engage said recesses and having inclined surfaces on one edge and a flat surface on the other, a pivoted catch on the cross-bar adapted to engage with a bearer to

prevent endwise movement of the bar when the latter is engaged with the recesses, and means adapted to secure the pivoted catch to either edge of the cross-bar for the purpose specified.

14. In a flat bed printing press, the combination with the bed and a cylinder bearer on each side thereof, of a series of recesses in one of the bearers, a corresponding series 10 of deeper recesses in the other bearer, a cross-bar having inclined surfaces on one edge and a flat surface on the other and adapted to be engaged with and disengaged from oppositely-located pairs of said recesses by endwise movement relatively thereto, a pivoted catch on the cross-bar adapted 15 to engage with a bearer to prevent such movement of the bar when the latter is engaged with the recesses, and means adapted 20 to secure the pivoted catch to either edge of the cross-bar for the purpose specified.

15. In a flat bed printing press the combination with the bed and a cylinder bearer on each side thereof, forming an uninterrupted track for the cylinder, of a series of 25 inwardly-opening recesses in one of the bearers, a corresponding series of deeper inwardly-opening recesses in the other bearer, a cross-bar having inclined surfaces on one edge and a flat surface on the other and 30 adapted to be engaged with and disengaged from oppositely-located pairs of said recesses by endwise movement relatively thereto, a pivoted catch on the cross-bar adapted to engage with a bearer to prevent such 35 movement of the bar when the latter is engaged with the recesses, and means adapted to secure the pivoted catch to either edge of the cross-bar for the purpose specified.

In testimony whereof I have affixed my 40 signature hereto.

JOHN WILLIAM LITTLER.
